UNITED STATES PATENT OFFICE.

EDWARD SWINDELL, OF GALVESTON, TEXAS.

AUTOMATIC SAFEGUARD FOR VEHICLES.

1,160,341.

Specification of Letters Patent. Patented Nov. 16, 1915.

Application filed February 26, 1915. Serial No. 10,663.

To all whom it may concern:

Be it known that I, EDWARD SWINDELL, a citizen of the United States, residing at Galveston, in the county of Galveston and State of Texas, have invented certain new and useful Improvements in Automatic Safeguards for Vehicles, of which the following is a full, clear, and exact specification.

This invention relates to fenders for automobiles and has for its chief object to prevent injury to persons and property from collisions.

Another object is to effect the automatic application of the brakes of the vehicle when the fender is compressed.

A further object is to provide a fender which will not only prevent a person from being run over by the front wheels of the vehicle, but will prevent injury due to contact with the fender, and still another object is to mount the fender in such a way that it will always be kept directly in front of the vehicle when going around curves as well as when running along a straight road.

25 Other objects will appear as the description proceeds.

The invention will be first hereinafter described in connection with the accompanying drawings, which constitute a part of this specification, and then more specifically defined in the claims at the end of the description.

In the accompanying drawings, wherein similar reference characters are used to designate corresponding parts throughout the several views:—Figure 1 is a side elevation of the front end portion of an automobile equipped with my improved fender. Fig. 2 is a plan view of the fender and the front portion of the chassis of the automobile. Fig. 3 is a front elevation of the fender. Fig. 4 is a side elevation of the carriage or support for the pneumatic fender globe, parts being shown in section, and the position of the globe thereon indicated in dotted lines. Fig. 5 is a plan view of the carriage or support for the globe. Fig. 6 is an under plane of the globe, and Fig. 7 is a rear elevation of the carriage and globe mounted thereon, the front wheels of the vehicle being shown but the other portions of the vehicle being broken away.

In the drawings, 1 designates the front portion of an automobile and 2 the front wheels thereof which are swiveled as usual for steering purposes. Arranged in front of

the body of the vehicle and between the front wheels thereof is a carriage or support 3 for a pneumatic globe or bulb 4 which is preferably of such dimensions as to extend well in front of the wheels and across the entire width of the vehicle.

The carriage 3 is generally circular in plan, as best illustrated in Fig. 5, and consists of a substantially round skeleton frame 5 supported on three rollers 6 and extending upwardly at its rear portion, as at 7, which is generally semi-circular in form so as to hold the globe 4 in proper position when a collision occurs and also when the vehicle is running in the ordinary way. The rollers 6 are preferably mounted on bowed strips 8, the middle one of which extends through a pocket 9 in the upwardly curved semi-circular rear portion of the carriage and up past the center of the globe, conforming to the curvature of the surface of said globe, as best shown in Fig. 1 at 10.

The carriage 3 is connected to the vehicle by a swivel or ball joint 11, best illustrated in Fig. 4, which is mounted on the front axle 12. Said carriage is also connected by links 13 to arms 14 on the stub axles of the front wheels, so that when said wheels are turned in steering, the carriage of the fender will be moved with them and always be positioned directly in front of the vehicle when going around curves as well as when running along a straight road.

In order to permit the carriage to be raised with its supporting rollers clear of the road when desired, as when running over a rough stretch of road, I provide a plate 15 hinged at 16 to the axle 12 and having its free lower end adapted to engage the carriage well below its ball joint. This hinged plate 15 may be operated or swung by means of a hand lever 17 pivoted at 18 and connected to said plate by a rod 19, whereby the front part of the carriage may be raised or lowered at will.

The frame 5 of the carriage may have a flange or bead 20 around its front and lateral edges, and the globe 4 may be provided with a correspondingly shaped depending tubular portion 21 which hangs over said flange or bead when the globe is in position over the carriage, as shown in Figs. 1, 3 and 4. Said tubular portion is connected to the globe by a skirt portion 22, the latter and the tubular portion being both hollow and communicating with the interior of the

globe so that they will all be inflated at the same time. A tube 23, containing a check valve 24, is used for inflating the globe and its tubular and skirt portions. Said tube 5 may, of course, be extended to any suitable place on the vehicle. Another tube 25 leads from the globe to a cylinder 26 connected in any suitable manner (not shown) to the brake applying mechanism, the object being 10 to utilize the pneumatic pressure which is expelled from the globe, when the same is compressed in a collision, for automatically applying the brakes of the vehicle and bringing the latter to a standstill. The tube 15 25 is provided with a check valve 27 near the cylinder 26 for preventing air from passing from said cylinder back into the globe. It will be understood that when a collision occurs, the pressure of the person 20 or article struck by the globular fender will cause the latter to collapse and force the air therefrom through the tube 25 into the brake applying cylinder, and that such person or article will be enveloped in the folds of the 25 collapsed pneumatic globe, thereby preventing serious injury to persons or property.

Having thus described my invention, what I claim as new and desire to secure by Letters Patent of the United States is:—

30 1. A pneumatic fender for vehicles in combination with means for applying the brakes of the vehicle when the fender is compressed, said fender being globular in form and collapsible whereby when brought 35 in contact with an object, the object will be enveloped in the folds of the fender.

2. A pneumatic fender for vehicles in combination with air brakes, and means for utilizing the air forced from said fender, 40 when the latter is compressed, for operating said air brakes.

3. A pneumatic fender for vehicles having means for supporting the same in front of a vehicle, said fender being globular in 45 form and collapsible whereby when brought in contact with an object, the object will be enveloped in the folds of the fender.

4. A globular fender for vehicles in combination with a swiveled carriage for supporting the same in front of a vehicle, and means for swinging said carriage up and 50

down from the interior of the vehicle, said fender being collapsible, whereby when brought in contact with an object, the object will be enveloped in the folds of the fender. 55

5. A globular fender for vehicles in combination with a swiveled carriage for supporting the same in front of a vehicle and having rollers on its front portion to engage the road, and means for swinging said carriage to raise the rollers off of the road for the purpose specified, said fender being collapsible, whereby when brought in contact with an object, the object will be enveloped in the folds of the fender. 60

6. A pneumatic fender for vehicles in combination with a carriage for supporting the same at the front of a vehicle, said carriage having a substantially circular base portion and a generally semi-circular upwardly curved rear portion forming a seat 70 for the pneumatic fender, the latter being substantially spherical in form.

7. A pneumatic fender for vehicles in combination with a carriage for supporting the same at the front of a vehicle, said carriage having a substantially circular base portion and a generally semi-circular upwardly curved rear portion forming a seat 75 for the pneumatic fender, the latter being substantially spherical in form, and the carriage having a portion projecting well above the center of the spherical fender and constituting a continuation of the curved rear portion for holding said fender in position when a collision occurs. 80

8. A globular fender for vehicles in combination with a carriage for supporting the same at the front of a vehicle, said carriage having a flange around its front and lateral edges, said fender being substantially spherical in form and having a tubular portion to fit over the flange on the fender, and a skirt portion connecting said tubular portion to the main part of the globular fender. 90 95

In testimony whereof I have signed my name to this specification in the presence of two attesting witnesses.

EDWARD SWINDELL.
